UNITED STATES PATENT OFFICE.

WILBUR M. WILLIAMS, OF HOLDEN, MISSOURI.

CHECK-ROW CORN-PLANTER.

SPECIFICATION forming part of Letters Patent No. 404,025, dated May 28, 1889.

Application filed October 24, 1888. Serial No. 289,049. (No model.)

To all whom it may concern:

Be it known that I, WILBUR M. WILLIAMS, a citizen of the United States, residing at Holden, in the county of Johnson and State of Missouri, have invented certain new and useful Improvements in Check-Rower Corn-Planters; and I do hereby declare the following to be a full, clear, and exact description of the invention, such as will enable others skilled in the art to which it appertains to make and use the same.

My invention relates to an improvement in check-rower corn-planters.

The object is to secure a check-rower which shall be actuated by the ground-wheel of the planter, and in which the feed-bar shall be so operated that the corn will be dropped in direct alignment across the field as well as in the direction in which the planter moves, thereby admitting of the cultivating of the corn in both directions.

With these ends in view my invention consists in certain features of construction and combinations of parts, as will be hereinafter described, and pointed out in the claims.

In the accompanying drawings, Figure 1 is a view of a portion of a corn-planter, showing the check-rower and parts immediately connected therewith in operative position. Fig. 2 is a plan view, and Figs. 3, 4, and 5 are detail views of parts.

A represents one of the side rails of the main frame of the planter, a the axle, and B one of the supporting-wheels. The main frame and wheels may be of any well-known or approved form, and, indeed, one of the prominent advantages of the check-rower mechanism which is about to be described lies in its adaptability to most of the corn-planters now in use without materially changing their construction.

The feed-hoppers C are located one on the right-hand side and the other on the left-hand side of the planter, as is usual, and the feed-bar c, for operating the valves to drop the corn, is located transversely of the planter, and has an endwise-sliding movement, as is common. The mechanism for operating the feed-bar c at the proper intervals is constructed and arranged as follows: A circular plate, D, having a hollow center to receive the hub of the wheel B, is provided on its inner face at its

outer edge with a series of ratchet-teeth, d, preferably sixty-six in number. A second circular plate, E, also having a hollow center 55 to receive the hub and corresponding with the plate D, is provided with an annular flange, e, on the side toward the plate D, which serves, when the parts are assembled, to space it from the plate D, and is also provided with 60 a series of ratchet-teeth, e', on its face toward the plate D at its inner edge, the teeth e' being the same in number and corresponding to the teeth d in the plate D, but having a pitch in the opposite direction. A ring, F, 65 having a width somewhat less than the distance between the opposite series of teeth, d and e', is adapted to loosely fit on the periphery of the flange e between the plates D and E, and said ring is provided with a short series of teeth, f f', preferably six in number, and located in corresponding positions on opposite sides of the ring, the teeth f being opposed in pitch to the teeth d, and the teeth f' being opposed in pitch to the teeth e'. The 70 width of the ring and its teeth is such that when the parts are assembled the ring can only turn the length of one tooth at a time, requiring at the end of each such movement to be slid laterally to free it from the abutting teeth before it can be turned another tooth-length.

The plates D and E and ring F are assembled by slipping the ring F over the flange e and then securing the plate E to the plate D 85 and the whole to the inner side of the wheel B around its hub by staple bolts or clips f², which embrace several of the spokes of the wheel and extend through the plates, thereby causing the whole to rotate with the wheel B. 90 From opposite points on the periphery of the ring F cams G and G' project for the purpose of operating the feed-bar c. The mechanism intermediate the said cams and the bar c is constructed as follows: A lengthwise-sliding bar, H, is supported transversely of the frame-piece A, and is provided with a roller, h, loosely mounted on a stud or pin projected rearwardly from its outer end. The outer end of the bar H is supported upon a 100 bracket, h', provided with upwardly-projected guide-lugs h², and to prevent undue sliding friction an anti-friction roller, h³, is journaled in the under side of the bar and

rests upon the upper face of the bracket. The roller h is located in the path of the cams G and G' , and the cam G is so twisted that it will engage the roller h and slide it, and hence the bar H , inwardly as it passes, and the cam G' is so twisted that it will engage the roller h and slide it, and hence the bar H , outwardly as it passes. The motions of the bar H are communicated to the feed-bar c by means of a bell-crank lever, I , pivoted intermediate its ends to a bracket-support, i , attached to the frame-piece A , and having one of its arms loosely connected with the inner end of the bar H , and its other arm loosely connected with the feed-bar c . The latter connection is preferably made by means of a plate, K , secured to the rear edge of the bar c , and provided with an oblong slot through it, in which the end of the arm of the bell-crank lever is loosely received.

To detect any gain or loss in distance between the successive droppings of the corn, and hence a failure to make a perfect alignment crosswise, a pair of markers, L , are hinged to the opposite sides of the planter, and their free ends are adapted to reach the ground at a distance from the center of a planted hill equal to about one-half the distance between two successive hills. The markers L are operated by cords l attached thereto, one to each, and leading therefrom over pulleys l' on standards l'' at the sides of the planter, thence to pulleys l''' located in, above, and slightly outside of the plane of the frame-piece A , and thence to a slide, M , supported in a guideway, N . The guideway N is held in an oblique position, preferably at an angle of about forty-five degrees below and slightly outside of the frame-piece A , by means of suitable hangers, O , secured to the said frame-piece. The slide M is adapted to enter the lower open end of the groove n in the guideway and to slide freely in said guideway to its upper end or a distance sufficient to allow the markers to rise and fall the desired amount. The lower end of the slide is provided with an eye or hook, m , to which the ends of the cords l are attached, and the said slide is held normally at the lower end of the groove n by means of a pivoted latch, m' , the lower end of which projects through the side of the guideway into engagement with the guide, a spring, m'' , being interposed between the upper end of the latch and the side of the guideway to hold it in locked adjustment. The lower end of the slide M is provided with an upwardly-projected finger, m''' , the purpose of which will hereinafter appear. In order to spring the latch m' and allow the markers to drop at the instant of planting a hill of corn, a lever, P , is pivoted to the frame-piece A in such position that its upper end will engage a shoulder, h^4 , on the rear edge of the bar H and its lower end will engage the forward end of the latch. Thus when the bar H is slid inwardly it will carry with it the upper end of the lever P , and its lower end will operate the latch

and release the slide, allowing the markers to drop. Furthermore, as the upper end of the lever P reaches the limit of its inward stroke it engages a guide, p , which projects from the frame-piece A and extends rearwardly a short distance beyond the rear edge of the bar H , whereby the end of the lever P is pressed rearwardly out of engagement with the shoulder h^4 , and is allowed to return to its normal position under the tension of the latch-spring, and the latch is thereby placed in position to retain the slide M when it shall have been again slid down the guideway.

The markers are elevated immediately after they have dropped by means of an arm, Q , which projects from the periphery of the ring F at a point just back of the cam G in position to engage the finger m'' on the slide. Such engagement takes place immediately after the markers have dropped, and the slide M is thereby slid downwardly along the guideway into position to be held by the latch, at which moment the arm Q releases it in the course of the revolution of the wheel B , and the markers are in position to be again dropped when the cam G shall have completed another revolution. The markers are only released at the moment of the inward slide of the bar H , and hence only fall with the planting of each alternate pair of hills of corn.

As the planter makes each successive course across the field one of the markers should fall in the same places as when it made its preceding course, and hence its deviation from such positions will denote either a loss or gain of distance, as the case may be.

In order to adjust the check-rower mechanism to correct the error, the ring F is, as heretofore described, capable of a sidewise movement between the plates D and E to allow it to turn one tooth at a time. The ring F is held normally in engagement with the teeth on the face of the plate E by means of a pair of springs, b , secured to the edge of the ring toward the plate D and bearing against the plate D . If, then, the marker is found to fall short of the place where it should fall, the error may be corrected by the driver pressing outwardly with his foot or hand against the cam G' , while the arm Q is engaged with the finger on the slide M . The result will be to throw the ring F out of engagement with the teeth on the plate E and allow it to slip back one tooth, thereby preventing the cam which operates the markers from reaching the roller h quite so soon as it otherwise would, and hence holding the markers suspended a little longer. As constructed, one tooth distance corresponds to about one and one-half inch of distance along the path of the planter. If the set back of one tooth distance is not enough to correct the error, the ring may be pressed outwardly one or more additional times until the required space is gained. If, on the other hand, the markers are falling in advance of their proper positions, it will be necessary to advance the ring

F one or more teeth to cause the markers to fall sooner than they otherwise would. This is accomplished as follows: To the rear edge of the arm Q a peculiarly-constructed knee-shaped pawl, R, is pivoted, so as to admit of a limited swing of the pawl between the arm Q and the periphery of the ring F. The upper or outer portion of said pawl is held normally away from the edge of the arm Q by means of a spring, r, seated in a recess in the pawl and pressing against the edge of the arm Q. The lower or inner portion of said pawl is provided with a perforation, S, extending in a direction parallel with a tangent to the ring F, the said perforation being gradually enlarged in a direction radial to the ring F, as it extends from the rear of the pawl toward the front of the same. In said perforation is seated the shank of a claw-bar, T, the same having a longitudinally-sliding movement in its seat, and its front end having a vertical play in the tapered perforation. The forward movement of the bar T is limited by a stud or pin, t, set in the shank and adapted to work in a groove, s, at the side of the perforation S, and the bar T is held normally in forward adjustment by means of a spring, U, secured at one end to the front of the pawl R, and its free end loosely engaging the bar T near its front end. The claw t' of the bar T is adapted to engage one of the teeth of the plate D when the pawl R is tilted forwardly, while the claw t' engages the opposite edge of the plate D to form a guide.

35 The driver when he desires to advance the ring F presses his foot against the rear of the pawl R, thereby causing it to tilt or rock over toward the front, causing the claw t' to engage a tooth on the plate D. This forms a bearing for the moment to retard the forward tilt of the pawl, and a further pressure will cause the pawl and arm Q, to which it is secured, to advance relatively to the plate D, the shank of the claw-bar receding through the perforation S the distance of one tooth, thereby allowing the ring F to be advanced one tooth. The moment the foot is removed the pawl, through the tension of the springs, as noted, will resume its normal position and 50 be in condition for a repetition of the operation.

It will be observed that the check-rower mechanism above described may be manufactured and shipped to be applied to the 55 planters now in use, its construction being such that it may be attached with but little fitting, and this of a simple and inexpensive character.

It is evident that slight changes might be 60 resorted to in the construction and arrangement of the several parts described without departing from the spirit and scope of my invention. Hence I do not wish to restrict myself strictly to the construction herein set 65 forth; but,

Having thus fully described my invention,

what I claim as new, and desire to secure by Letters Patent, is—

1. In a check-rower mechanism, the combination, with two sets of oppositely-disposed ratchet-teeth actuated by the planter-wheel, of a toothed ring interposed between the said sets of ratchet-teeth, means for throwing the toothed ring into engagement with either set of ratchet-teeth, the feed mechanism, and means for communicating the motion of the toothed ring to the feed mechanism, substantially as set forth. 70

2. The combination, with the feed mechanism and the ground-wheel of the planter, of two circular series of ratchet-teeth secured to the ground-wheel and concentric therewith, and a cam-carrying ring for operating the feed mechanism, the cam-carrying ring being loosely mounted between the said series of ratchet-teeth and having interlocking ratchet-teeth on its opposite edges, substantially as set forth. 80

3. The combination, with the feed mechanism, the ground-wheel of the planter, and operating devices connecting the ground-wheel and feed mechanism, of a pair of rising and falling markers, an inclined guideway, a slide seated in said guideway, flexible connections between the slide and the markers, and a holding and releasing device in connection with the slide and feed mechanism for operating the slide, and hence the markers, simultaneously with the dropping of the corn, substantially as set forth. 90

4. The combination, with the feed mechanism, the ground-wheel of the planter, and operating devices connecting the ground-wheel with the feed mechanism, of a pair of rising and falling markers, a guideway, a slide seated in the guideway, connections between the slide and markers, a spring-actuated latch to hold the slide, and a latch-operating lever in engagement with the spring-latch and with the feed mechanism, substantially as set forth. 105

5. The combination, with the feed-bar and the ground-wheel adapted to actuate the feed-bar, of a guideway, a slide seated in the guideway, a pair of rising and falling markers connected with the slide, a spring-actuated latch, a latch-operating lever in engagement with the feed-bar, and a guide located in the path of the latch-operating lever to throw it out of engagement with the feed-bar as it reaches the end of its stroke, substantially as set forth. 115

6. The combination, with the feed mechanism, the rotary cam and its support, the rising and falling markers, and the slide connected with the markers, of the toothed plate between which the cam-support is mounted and the springs for holding the cam-support in normal engagement with one of the toothed plates, substantially as set forth. 125

7. The combination, with the feed mechanism, the rotary cam-support, the rising and

falling markers, and the slide connected with the markers, of the slide-actuating arm on the cam-support, substantially as set forth.

8. The combination, with the rotary cam-support and the circular series of teeth between which it is mounted, of the pawl pivoted to an arm on the periphery of the cam-support, the said pawl carrying a claw-bar adapted to engage one of the series of teeth when the pawl is rocked forward, substantially as set forth.

9. The combination, with the rotary cam-support and the series of teeth between which

it is mounted, of the pawl pivoted to an arm on the periphery of the cam-support, the said pawl carrying a spring-actuated claw-bar adapted to engage one of the series of teeth, and a spring to hold the pawl normally tilted away from the arm to which it is pivoted, substantially as set forth. 15 20

In testimony whereof I have affixed my signature in presence of two witnesses.

WILBUR M. WILLIAMS.
